US0D1091465S

(12) **United States Design Patent** (10) **Patent No.:** **US D1,091,465 S**
(45) **Date of Patent:** **** Sep. 2, 2025**

(54) **WIRELESS CHARGER**

(71) Applicant: **Shenzhen Yifeng Intelligent Technology Co., Ltd.**, Shenzhen (CN)

(72) Inventor: **Ning Liu**, Shenzhen (CN)

(73) Assignee: **Shenzhen Yifeng Intelligent Technology Co., Ltd.**, Shenzhen (CN)

(**) Term: **15 Years**

(21) Appl. No.: **29/940,853**

(22) Filed: **May 6, 2024**

(30) **Foreign Application Priority Data**

Feb. 7, 2024 (CN) 202430083222.9

(51) **LOC (15) Cl.** **13-02**

(52) **U.S. Cl.**

USPC **D13/108**

(74) *Attorney, Agent, or Firm* — George D. Morgan

(57) **CLAIM**

The ornamental design for a wireless charger, as shown and described.

DESCRIPTION

FIG. 1 is a front perspective view of a wireless charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of its folded state thereof; and,

FIG. 10 is a rear perspective view of its folded state.

The broken lines in the drawings illustrate the portions of the wireless charger, which form no part of the claimed design.

1 Claim, 10 Drawing Sheets
